UNITED STATES PATENT OFFICE

120,614

DESIGN FOR A GLASS JUG OR ARTICLE OF SIMILAR NATURE

Albert J. Dreitzer, New York, N. Y., assignor to
The Federal Glass Company, Columbus, Ohio,
a corporation of Ohio

Application March 29, 1940, Serial No. 91,348

Term of patent 7 years

To all whom it may concern:

Be it known that I, Albert J. Dreitzer, a citizen of the United States of America and a resident of New York, in the county of New York and State of New York, have invented a new, original and ornamental Design for a Glass Jug or Article of Similar Nature, of which the following is the specification, reference being had to the accompanying drawing, forming a part thereof.

Figure 1 is a perspective view of the glass jug

or article of similar nature, showing my new design.

Figure 2 is a top plan view thereof.

Figure 3 is a vertical sectional view, on a reduced scale, taken along line 3—3 of Figure 2.

I claim:

The ornamental design for a glass jug or article of similar nature, substantially as shown.

ALBERT J. DREITZER.
